BRICK EMBOSSED DEVICE

Ross A. Clem, West Terre Haute, Ind., assignor to
Joseph Entwistle, Terre Haute, Ind.

Application October 16, 1933, Serial No. 693,807

9 Claims. (Cl. 25—1)

This invention relates to the art of brick making machines and particularly to means for embossing or forming patterns or designs on the bricks as they may be cut from the column of clay. The invention is intended to be applied to that type of a brick cutter wherein a movable carriage receives a column of clay and a revolving reel is carried by the carriage to cut through the column by a multiple number of wires spaced 5 apart to define the thicknesses of the bricks, such machine being well known to those versed in the art and the details of which do not specifically enter into my invention.

An important object of the invention is to provide an attachment which may be applied to the type of machine above indicated so that each brick as cut may be embossed or intended to produce the desired face thereon simultaneously with the cutting of the brick from the column of clay. It is a further object of the invention to provide such a device that may be applied to the machine without interference of other parts thereof and which will work automatically therewith.

A further important object of the invention is to provide means for retaining each individual brick rigidly in place on the platen as the cutting wires move through the clay column whereby the cuts through the column are in planes perpendicular to the axis of the column and do not curve 30 as would be the case should the column accidentally be shifted while the cutting is taking place.

These and other objects and advantages will become apparent to those versed in the art by the following description of one particular form of the invention as illustrated by the accompanying drawings, in which

Fig. 1 is a fragmentary perspective view of a brick cutter with a single embossing device in position;

Fig. 2, a fragmentary top perspective view, and Fig. 3, a detail in fragmentary side elevation of the embossing attachment.

Like characters of reference indicate like parts throughout the various views in the drawings.

Referring to the drawings, the cutter carriage of the cutting mechanism carries the usual platen 10 supported from a horizontal shaft 11 by means of brackets 12 carried thereon. This platen 10 is in reality a plurality of individual brackets spaced apart sufficiently to permit the cutting wires 13 to pass therebetween. As is the usual practice, in machines of this type, a column of clay rectangular in shape is extruded to extend on this platen 10 and then the reel 14 is revolved to

carry the wires 13 through this column to cut through it to form the individual bricks.

To the above described mechanism I attach a plurality of embossing devices which will now be described in detail. Referring first to Fig. 3, I form a casting 15 to have a body adapted to fit over the upper side of the bracket 12 and to be there secured by substituting bolts 16 for the shorter bolts 17, Fig. 1, which were employed to retain the individual members of the platen 10 against the under sides of the brackets 12. The casting 15 is sufficiently narrow so as to fit between the wire holding members 18 which are carried on the shaft 11 between brackets 12.

The casting 15 extends forwardly and downwardly below the shaft 11 to have a head 19 centrally and vertically through which is slidably positioned a rod 20. Secured to the under side of this rod 20 is a plate 21 which is parallel to the lower face of the platen 10. Guide pins 22 and 23 respectively are fixed to the plate 21 and extend upwardly slidably within bores provided in the head 19 whereby the plate 21 may not rotate horizontally but is maintained in fixed alignment.

Each of these pins 22, 23 are preferably provided with some means for preventing the rapid passage of air past the pins within the bore, such means being here shown as a cup leather 24 on the upper end. It is desired that as the plate 21 may be pulled upwardly by the rod 20, these pins 22 and 23 as their upper ends approach the ends of their respective bores will tend to compress the air therein so as to provide an increasing resistance to such moving of the plate and thereby produce a cushioning effect.

The plate 21 is normally held up against the head 19 by means of a spring 25 which surrounds the rod 20 to compressibly bear between the top side of the head 19 and a washer 26 held by a pin 27 passing through the rod. The upper end of the rod 20 is screwthreaded to receive a head 28, the threaded connection providing means for adjusting the head 28 upwardly or downwardly therealong.

The upper end of the head 28 is bifurcated to receive therethrough the operating lever 29. This lever 29 is pivotally connected to the casting 15 to extend through the slot in the head 28 and normally substantially horizontally therebeyond. A lug 30 is provided on the under side of the lever 29 to be preferably rounded and so located as to be in contact with the head 28 at the bottom of the slot whereby this lug may slide on the head 28 as it may be depressed by pushing down on the outer free end of the lever 29. A pin 31

loosely passes through the lever 29 between the upper ends of the head 28 so as to prevent the lever 29 from accidentally flying out of the slot in the head 28, the actual bearing between the 5 lever and the head being at the under side of the lug 30 and not at the pin 31. To the under side of the plate 21 may be attached any suitable embossing die 32, here shown as by means of bolts 33.

Referring now to Figs. 1 and 2, a bar 34 is fixed 10 to the reel to be back of each set of wires 13. On this bar is carried a presser foot 35 for each lever 29. This foot 35 consists of a short plate rockably attached to the forward upper side of the bar 34 to extend rearwardly therefrom so as to be 15 in the path of the respective lever 29 as the reel 14 may be revolved. A bolt 36 extends upwardly through the bar 34 to be stopped by a head thereunder and is slidably passed through the foot 35 to extend upwardly therebeyond to carry a spring 20 37 therearound bearing between the top of the foot 35 and a washer 38 adjustably carried on the bolt 36 by the wing nut 39.

While but one embossing device is shown in Fig. 1, it is to be understood that there is one 25 such device between each pair of wires 13, only one such device being shown in Fig. 1 for the sake of clearness in illustrating the relative positions of the various parts. In operation, the bars 34 are so located on the reel 14 that when the 30 wires 13 come into contact with the corner of the column of clay then on the platen 10, the feet 35 have come into contact with the ends of the levers 29 and carried them down to the positions indicated by the dash lines in Fig. 3, whereupon 35 the embossing plate 32 is brought against the top of the clay column to compressly engage that column with the platen 10 so that as the wires 13 continue to cut through the column, the bricks thereby being cut off are firmly held against longitudinal movement on the platen 10 and at the 40 same time, sufficient pressure is exerted by the plate 32 to impress whatever design is to be formed by that plate upon the edge of the brick. Of course the plate 32 may remain perfectly 45 smooth if desired so that the device may be used solely for the purpose of preventing movement of the bricks as they are cut if a design is not to be impressed simultaneously. By adjusting the wing nuts 39 the pressure applied on the bricks 50 may be controlled and should the pressure become too great, the members 35 will be forced upwardly to further contract the springs 37 even so far as to permit the members 35 to slide on past the ends of the levers 29 when in such raised 55 positions. It is to be understood that in any event the feet 35 are lifted eventually as the reel continues to carry the wires through the clay column so that toward the end of the cutting operation, the levers 29 are released in any event. The 60 pressure by the plates 32 on the bricks serves to stop any relative motion initially between the platen and the clay column at the beginning of the cutting operation, the clay column then having no tendency to have relative motion over the 65 platen.

While I have here shown and described my invention in the one form as now best known to me, it is obvious that structural changes may be made without departing from the spirit of the 70 invention and I, therefore, do not desire to be limited to that precise form beyond the limitations as may be imposed by the following claims.

I claim:

1. A presser attachment for a brick cutting 75 mechanism comprising a relatively stationary

body, a plate, a lever, means for moving the plate by moving the lever and means comprising a hinged foot yieldingly actuated by the movement of the cutting mechanism for moving the lever to lower the plate.

2. A presser attachment for a brick cutting mechanism comprising a relatively stationary body, a plate, a rod slidably carried by the body and secured to the plate, a lever pivotally carried by the body in contact with said rod whereby rocking of the lever will lower the rod, and means carried by said mechanism comprising a hinged foot yieldingly striking and moving said lever and lowering said plate.

3. A presser attachment for a brick cutting mechanism comprising a relatively stationary body, a plate, a rod slidably carried by the body and secured to the plate, a lever pivotally carried by the body and in contact with said rod whereby rocking of the lever will lower the rod, and means carried by said mechanism to strike and move said lever to lower said plate, spring means for returning said plate, and cushion means retarding said return.

4. A presser attachment for a brick cutting mechanism comprising a relatively stationary body, a plate, a rod slidably carried by the body and secured to the plate, a lever pivotally carried by the body and in contact with said rod whereby rocking of the lever will lower the rod, and means carried by said mechanism to strike and move said lever to lower said plate, said means comprising a foot rockably attached to the mechanism, and a spring yieldingly retaining the foot in the path of the lever.

5. For a brick cutting mechanism, the combination with a platen adapted to receive a column of clay thereover, a plurality of column cutting wires, and means for carrying said wires through the column; of a plurality of embossing devices 40 one each being mounted within the space between adjacent wires and being spaced above and fixed relative to said platen; each of said devices comprising a body, a rod slidably carried by the body to reciprocate toward and away from the platen, 45 a plate on the rod, a lever rockably carried by the body and engaging with said rod; and feet carried by said means in the paths of the levers located to strike and move the levers to depress the plates against said column upon said wires 50 initially starting to cut into the column.

6. For a brick cutting mechanism, the combination with a platen adapted to receive a column of clay thereover, a plurality of column cutting wires, and means for carrying said wires through 55 the column; of a plurality of embossing devices one each being mounted within the space between adjacent wires and being spaced above and fixed relative to said platen; each of said devices comprising a body, a rod slidably carried by the body 60 to reciprocate toward and away from the platen, a plate on the rod, a lever rockably carried by the body and engaging with said rod; and feet carried by said means in the paths of the levers located to strike and move the levers to depress 65 the plates against said column upon said wires initially starting to cut into the column, and springs yieldingly retaining said feet against said levers permitting the feet to shift from contact with the levers upon a predetermined pressure 70 being applied by the feet on the levers.

7. For a brick cutting mechanism, the combination with a shiftable carriage having a platen over which a column of clay is extruded, and a 75 reel carried by the carriage having a plurality of

spaced apart wires for cutting through the column to slice off lengths into bricks upon rotation of the reel; of a plurality of embossing devices, one for each brick formed, said devices being located

5 one within each space between adjacent wires and mounted on said carriage to be spaced above and fixed relative to said platen, a reciprocating plate carried by each device, a lever extending from each device for reciprocating its 10 plate, and means carried by said reel located to intercept said levers to carry said plates against the clay column in timed sequence with said wires.

8. For a brick cutting mechanism, the combination with a shiftable carriage having a platen over which a column of clay is extruded, and a reel carried by the carriage having a plurality of spaced apart wires for cutting through the column to slice off lengths into bricks upon rotation of 15 the reel; of a plurality of embossing devices, one for each brick formed, said devices being located one within each space between adjacent wires and mounted on said carriage to be spaced above and fixed relative to said platen, a reciprocating plate 20 carried by each device, a lever extending from each device for reciprocating its plate, and means carried by said reel located to intercept said levers to carry said plates against the clay column in timed sequence with said wires, 25 said means comprising a bar extending across the reel and a foot on the bar for each lever, each of said feet being rockably attached normally to swing out of the way of said levers upon movement therewith, and a spring yieldingly resisting said swinging.

to carry said plates against the clay column in timed sequence with said wires, said means comprising a bar extending across the reel and a foot on the bar for each lever.

9. For a brick cutting mechanism, the combination with a shiftable carriage having a platen over which a column of clay is extruded, and a reel carried by the carriage having a plurality of spaced apart wires for cutting through the column to slice off lengths into bricks upon rotation of the reel; of a plurality of embossing devices, one for each brick formed, said devices being located one within each space between adjacent wires and mounted on said carriage to be spaced above and fixed relative to said platen, a reciprocating plate carried by each device, a lever extending from each device for reciprocating its plate, and means carried by said reel located to intercept said levers to carry said plates against the clay column in timed sequence with said wires, 10 said means comprising a bar extending across the reel and a foot on the bar for each lever, each of said feet being rockably attached normally to swing out of the way of said levers upon movement therewith, and a spring yieldingly 15 resisting said swinging.

ROSS A. CLEM.
